ROAD CHAIR

Howard W. Nester, Worcester, Mass., assignor to
Parker Wire Goods Company, Worcester, Mass.,
a corporation of Massachusetts

Application December 3, 1931. Serial No. 578,729

8 Claims. (Cl. 94—8)

This invention relates to devices for holding reinforcing rods in position during cement construction operations.

The invention is particularly adapted for use in supporting the wire rod reinforcements or "mats" used in cement road building.

Devices for such purposes have been heretofore produced and one such device is shown in the prior patent to Ribb, No. 1,830,888 issued November 10, 1931.

It is the general object of my present invention to improve the construction of such road chairs in such manner that a road chair of greatly increased strength and utility may be produced at only a very slight increase in the cost of either material or labor.

With this general object in view, important features of my invention relate to the provision of a bracing element in a road chair of the Ribb 20 type and also to the provision of an intermediate retaining or locking member.

My invention further relates to arrangements and combinations of parts which will be herein-after described and more particularly pointed out 25 in the appended claims.

A preferred form of my invention, together with a modification thereof, is shown in the drawings, in which

Fig. 1 is a perspective view of one form of my 30 improved road chair;

Fig. 2 is a side elevation thereof, looking in the direction of the arrow 2 in Fig. 1;

Figs. 3 and 4 are end elevations of the road chair, looking in the directions of the arrows 35 3 and 4 in Fig. 2;

Fig. 5 is a side elevation of a modified construction;

Figs. 6 and 7 are end views thereof, looking in the directions of the arrows 6 and 7 in Fig. 5, 40 and

Fig. 8 is a detail perspective view of a further modification.

Referring first to Figs. 1 to 4, I have shown a form of my invention in which the entire road 45 chair, with the exception of the sheet metal base 10, is formed from a single piece of wire rod. This road chair is adapted to secure crossed reinforcing rods R and S in assembled relation and to space these rods at a predetermined distance 50 above an underlying surface, such as the sub-structure or foundation of a cement road.

My improved road chair comprises a longitudinally extending intermediate connecting portion 12 having one end bent to form an upwardly 55 displaced loop 14, a downwardly displaced loop 15 and an upwardly displaced loop or end portion 16. The lower rod R rests in the loop 15 and the upper rod S extends transversely under the loops 14 and 16 and is retained in position 60 thereby.

At its opposite end, the intermediate portion 12 is bent transversely, as indicated at 18, to provide an additional support for the lower rod R. The wire rod is then bent upward to provide an offset portion 19 and downward to provide a depending portion 20. The offset portion 19 prevents relative lateral displacement of the rod R after it has been placed in position.

The depending portion 20 is provided with a base portion having angularly disposed parts 22 and 23, and the wire rod extends in an upwardly inclined direction from the end of the part 23 to form a brace 25.

This brace 25 is preferably welded or otherwise secured to the intermediate portion 12 at the 75 crossing point 26 and the upper end of the brace 25 is bent transversely to provide an intermediate retaining or locking member 27. The outer portion of this retaining member 27 is displaced downwardly, as indicated at 28, and the extreme outer end is then inclined upwardly, as indicated at 29.

When the parts are assembled, the retaining or locking member 27 loosely overlies the lower 85 rod R and prevents upward displacement thereof to such an extent as to permit the rod R to slip sideways over the offset portion 19.

The base 10 is permanently secured to the base 90 members 22 and 23 by welding or otherwise, and affords an extended and substantial footing for the road chair, particularly when used on a soft or uneven foundation surface.

The brace 25 forms in effect a second leg or support between the base 10 and the rod-supporting portions of the chair and greatly strengthens 95 the chair against distortion or displacement when an unusual strain is placed thereon.

My improved road chair thus possesses substantial advantages over the device shown in the Ribb patent above identified.

In Figs. 5 to 7, I have shown a slightly modified construction, in which the road chair is formed of two separate pieces of wire rod, in addition to the base plate 30.

The main part of the chair is formed from a 105 piece of wire rod having an intermediate portion 31 looped upwardly at 32, downwardly at 33 and again upwardly at 34, as in the form previously described.

The opposite end of the intermediate portion 31 is bent directly downward at 36 and then laterally to provide a base portion 37 adapted to be welded or otherwise secured to the base plate 30.

The outer end of the base portion 37 is then 115 bent upward, as indicated at 38, and is then looped and bent transversely to provide an offset portion 39 and a rod-supporting portion 40. The end of the rod-supporting portion 40 is preferably welded or otherwise secured at 41 to the upright portion 36.

A brace rod 42 is welded or otherwise secured to the upright portion 36 at the point 43 and is similarly secured to the intermediate portion 31 at the point 44.

5 The upper end of the brace rod 42 is bent laterally to provide a retaining or locking member 45 of similar construction to the locking member 27 shown in Figs. 1 and 4.

10 While this form of my invention is of slightly different mechanical construction and involves the use of two pieces of wire rod instead of one, the use and advantages are substantially the same as in the form previously described. In both cases the provision of the brace rod and intermediate 15 retaining or locking member adds greatly to the strength and utility of the device and makes the chair much more satisfactory for its intended purposes.

15 Both forms of these road chairs are easily assembled with the reenforcing rods and when once in position are not readily displaced.

20 In Fig. 8, I have shown a further form of my invention which is in general similar to the construction shown in Fig. 1 but in which the lower 25 end of the depending portion 50 is bent to form an enlarged base portion 51, preferably of substantially circular outline. The brace member 52 is shown as being formed from a separate piece 30 of wire rod, welded to the member 50 at the point 53 and welded to an outer face of the intermediate member 54 at the point 55. The upper end of the brace member 52 is preferably extended to provide a locking portion 56, as in the forms previously described. With this construction a substantial base area is secured and under ordinary 35 conditions the separate sheet metal base may be omitted, as also in the forms shown in Figs. 1 to 7.

40 While I have used the term "road chair" in the specification and claims, it will be understood that my invention is not limited to use in road construction but that it is equally adapted for forming reenforcing mats for use in building or floor construction or for any other purposes. The term "road chair" is to be considered as descriptive only 45 and not as a limitation.

Having thus described my invention and the advantages thereof, I do not wish to be limited to the details herein disclosed, otherwise than as set forth in the claims, but what I claim is:—

50 1. A road chair comprising a substantially flat extended base plate, an approximately horizontal intermediate section having upwardly and downwardly offset rod-engaging portions at one end thereof and having a rod-engaging portion at the other end extended downwardly to engage said base plate, and a brace member connected to said supporting portion and permanently secured to said intermediate section at a point between the ends thereof and substantially spaced from said ends, all parts of said road chair except 55 the base plate being formed from a single continuous piece of wire rod.

60 2. A road chair comprising an approximately horizontal intermediate section having upwardly and downwardly offset rod-engaging portions at one end thereof and having a downwardly extended supporting portion at the other end, the end of said supporting portion being offset laterally to provide a base portion and being again offset upwardly and laterally to provide an additional rod-engaging brace member, said brace member being permanently secured to said intermediate section at a point between the ends thereof and substantially spaced from said ends.

65 3. A road chair comprising an approximately horizontal intermediate section having upwardly and downwardly offset rod-engaging portions at one end thereof and having a downwardly extended supporting portion at the other end, the end of said supporting portion being offset laterally to provide a base portion and being again offset upwardly and laterally to provide an additional rod-engaging portion, the extreme end of which is permanently secured to said downwardly-extended portion.

70 4. A road chair comprising an approximately horizontal intermediate section having upwardly and downwardly offset rod-engaging portions at one end thereof and having a rod-engaging supporting portion at the other end, and a brace member connected to said supporting portion and permanently secured to said intermediate section at a point between the ends thereof and substantially spaced from said ends.

75 5. A road chair comprising an approximately horizontal intermediate section having upwardly and downwardly offset rod-engaging portions at one end thereof and having a rod-engaging supporting portion at the other end, and a brace member connected to said supporting portion and permanently secured to said intermediate section at a point between the ends thereof and substantially spaced from said ends, said brace member being extended above said intermediate 80 section and having a laterally offset portion constituting a rod-retaining member.

85 6. A road chair comprising an approximately horizontal intermediate section having upwardly and downwardly offset rod-engaging portions at one end thereof and having a rod-engaging supporting portion at the other end, said latter portion being extended downwardly and having an offset base portion substantially enclosing a substantial area, and a brace member connecting said base portion to said intermediate section and permanently secured to said intermediate section at a point between the ends thereof and substantially spaced from said ends.

90 7. A road chair comprising an approximately horizontal intermediate section having upwardly and downwardly offset rod-engaging portions at one end thereof and having a rod-engaging supporting portion at the other end, said latter portion being extended downwardly and having an offset base portion substantially enclosing a substantial area, and a brace member connecting said base portion to said intermediate section and permanently secured to said intermediate section at a point between the ends thereof and substantially spaced from said ends, said brace member being extended to constitute and provide an upper rod-retaining device.

95 8. A road chair comprising an approximately horizontal intermediate section having upwardly and downwardly offset rod-engaging portions at one end thereof and having a downwardly extended supporting portion at the other end, the end of said supporting portion being offset laterally to provide a base portion and being again offset upwardly and laterally to provide an additional rod-engaging portion, the extreme end of which is permanently secured to said downwardly-extended portion, and a brace member connected to said supporting portion and permanently secured to said intermediate section at a point between the ends thereof and substantially spaced from said ends.

HOWARD W. NESTER.
